UNITED STATES PATENT OFFICE.

GUY H. MILLER, OF CAMBRIDGE, MASSACHUSETTS, ASSIGNOR OF ONE-HALF TO HARRY C. DIAMOND, OF ARLINGTON HEIGHTS, MASSACHUSETTS.

WRENCH.

Application filed July 23, 1925. Serial No. 45,654.

My invention relates to improvements in wrenches of the type having one or more pivoted jaws, and it consists in the combinations, constructions and arrangements herein described and claimed.

An object of the invention is the provision of a wrench having a pair of relatively adjustable jaws at one end of the body of the wrench and adapted to be adjusted quickly and easily and to be effectively retained in adjusted position with respect to each other so that the jaws will firmly grip a nut or like object with which they are engaged when the jaws are in any one of a plurality of possible adjustments with respect to each other.

A further object of the invention is the provision of a wrench having a pair of pivoted jaw members at one end of the wrench, and substantially in line with the handle of the wrench so that the wrench can be manipulated to turn a nut or like object which is located in a space of a relatively slight area.

A further object of the invention is the provision of a wrench of the character described which will be reliable in use, economical to manufacture, and thoroughly practical commercially.

Other objects and advantages of the invention will be apparent from the following description, considered in conjunction with the accompanying drawings, in which:

Figure 1 is a perspective view of the improved wrench,

Figure 2 is a fragmentary view mainly in longitudinal vertical section and partly in side elevation, showing to advantage the means which adjustably connect the jaws of the wrench, and

Figure 3 is a perspective group view showing the jaws of the wrench separated from the body of the wrench, together with certain of the elements which are associated with the jaws of the wrench.

The improved wrench comprises a body consisting of a head portion 1 and a handle portion 2. The head portion 1 is bifurcated for part of its length by a vertical slot 3 which is extended rearwardly at its upper end as indicated at 4, as shown to advantage in Figures 2 and 3. The furcations which are produced by the slot 3 in the head portion 1 are cut away at their lower edges to terminate above the level of the lowest part of the remainder of the head portion 1, and

to produce sockets, as at 5 which are located at opposite sides of a downwardly and forwardly projecting lug portion 6 at the lower and rearward end of the slot 3.

The invention contemplates the provision of a pair of jaw members as indicated at 7 and 8 respectively. The jaw member 7 is the upper jaw member, and has a shank 7^a which is formed with forks 9 at its extremity straddling one end of a link 10, and attached to that link by a pivot element 11. The lower end of the link 10 is pivotally supported within the extension 4 of the slot 3 by means of a pivot element 12. The pivot element 12 has the ends thereof fast in aligned openings 13 in the furcations of the head portion 1 of the body of the device.

The lower jaw 8 has a shank 14 which is provided at its end with a pair of spaced forks or attaching ears 15. The latter straddle the lug 6 and are received in the recesses 5. A pivot pin 16 extends through aligned openings in the forks 15 and the lug 6 and attaches the lower jaw pivotally to the head portion 1 of the body of the device, the pivot element 16 being parallel to the pivot elements 11 and 12.

The lower jaw 8 is enlarged vertically intermediate its length and forwardly of the furcations of the head portion 1, as indicated at 17. The forward end wall 18 of the enlargement 17 on the lower jaw extends substantially at right angles to the direction of length of that jaw for a purpose to be presently described. A vertical bore 19 extends through the enlarged middle portion of the jaw 8, and is intersected by a transverse bore 20. A vertical bore 21 extends through the upper jaw 7 substantially in line with the bore 19, and is intersected by a transverse aperture 22. An adjusting rod has a screw portion 23 in threaded engagement with a threaded transverse bore 24 in a block 25 which is circular in cross sectional contour, and is rotatably received in the transverse bore 20 of the lower jaw 8. The screw portion 23 of the adjusting rod is of less diameter than the bore 19, and therefore is loosely received in the latter so that slight rotary movement of the block 25 in the bore 20 is possible. The screw 23 extends in the bore 21 through the transverse aperture 22 and carries an operating wheel 26 which protrudes from the opening 22 at opposite sides of the upper jaw 7, and has the periphery 110

thereof formed with a circumferentially extending series of ridges as clearly shown, so that the operating wheel 26 can be conveniently and firmly gripped between the fingers 5 of a hand and manipulated to turn the adjusting rod. The wheel 26 may be secured to the screw 23 in any suitable known manner, no means therefor being shown in the drawings, so that the wheel 26 will be rigid 10 with the screw 23. It of course is obvious that the periphery of the wheel 26 may be knurled or otherwise roughened instead of being provided with the series of ridges as shown, without departing from the spirit 15 and scope of the invention.

The portion of the adjusting rod that extends from the operating wheel 26 through the upper part of the bore 21 is formed with a smooth peripheral surface as indicated 20 at 27. This upper end portion of the adjusting rod may be journaled in the corresponding portion of the bore 21, while the threaded portion of the adjusting rod that extends in the bore 21 is of less diameter than the corresponding portion of the bore 21, and is 25 loosely received in the latter.

An expansion spring 28 is disposed between the shanks of the jaw members 7 and 8 in the slot 3, and tends to spread the jaws 30 apart. The opposite ends of the expansion spring 28 may be disposed on alined pin projections 29 and 30 on the confronting faces of the shanks of the jaws 8 and 7, respectively, and these pin projections cooperate 35 with the furcations of the head portion of the body 1 to prevent accidental displacement of the expansion spring 28 from the position shown in Figure 2.

From the foregoing description of the 40 various parts of the device, the operation thereof may be readily understood. The front end wall 18 of the upwardly extending enlargement on the jaw will partially or completely close the space between the forward 45 end portions of the jaws 8 and 7, according to whether the jaws are completely closed or not. The position of the jaws with respect to each other can be varied quickly and easily by manipulating the operating wheel 50 26 to turn the adjusting rod, and thereby to move the jaws toward or away from each other. The jaws therefore can be quickly adjusted to grip a nut or other object or any one of a plurality of sizes within a considerable range. It is obvious that the 55 wrench may be adapted for use to grip a circular object such as a length of pipe, merely by placing serrations or otherwise roughening the confronting faces of the outer 60 end portions of the jaws. The spring 28 will function in cooperation with the adjusting screw and block 25 to maintain the jaw 7 substantially parallel with the jaw 8 in any one of the various adjustments which may 65 be effected by manipulating the operating

wheel 26. Since the jaw members extend from the head portion of the body of the device substantially in line with the body of the device, the space between the jaws for the reception of the article that is to be gripped between the jaws will be open at one end of the device, and it therefore is obvious that the device can be inserted in a space of relatively slight area and placed in engagement with a nut or other object that is located in that space, and then manipulated to turn the nut or like object. It also is manifest that a relatively great leverage can be obtained to effect turning of a nut or like object when the free end portion of the handle of the device is grasped and the nut or object that is to be turned is gripped between the jaws of the device.

Obviously, the invention is susceptible of embodiment in forms other than that which is illustrated in the accompanying drawings, and I therefore consider as my own all such modifications and adaptations thereof as fairly fall within the scope of the appended claims.

I claim:—

1. A wrench comprising a body, a pair of jaw members pivotally attached to said body at one end of the latter, said jaws having alined bores in the extending portions thereof, one of said jaws having a transverse bore intersecting said first named bore therein, and the other jaw having a transverse aperture intersecting said bore in that jaw, a screw loosely received in the alined bores of said jaws, an operating wheel carried by said screw and protruding from said transverse aperture in one of said bores, a retaining block journaled in the transverse bore of the other jaw, said retaining block having a transverse bore in threaded engagement with said screw, and an expansion spring disposed between said jaws rearwardly of said screw.

2. A wrench comprising a body having a head portion bifurcated at its extremity, a pair of jaws, one of said jaws being pivotally attached to said head portion at the lower side of the furcations of said head portion, the other jaw having a shank extending between said furcations, a link pivotally attaching the shank of said last named jaw to said head portion so that said pivoted jaws can swing in one direction in the same plane, said first named jaw being enlarged toward the opposite jaw intermediate its length, and having a transverse bore formed through said enlarged portion thereof, a block journaled in said transverse bore, said first named jaw having a vertical bore intersecting said transverse bore, and the second jaw having a vertical bore substantially in alinement with the vertical bore of the first jaw, the vertical bore of the second jaw being intersected by a transverse opening in

the second jaw, an adjusting rod having the upper end portion thereof journaled in said vertical bore of the second jaw above the transverse opening in said second jaw and having a screw portion extending loosely in said vertical bores of said jaws and in threaded engagement with a transverse bore in said block, and an operating wheel rigid with said adjusting rod and protruding from 10 said transverse opening in the second jaw.

3. A wrench comprising a body having a head portion bifurcated at its extremity, a pair of jaws, one of said jaws being pivotally attached to said head portion at the lower 15 side of the furcations of said head portion, the other jaw having a shank extending between said furcations, a link pivotally attaching the shank of said last named jaw to said head portion so that said pivoted jaws 20 can swing in one direction in the same plane, said first named jaw being enlarged toward the opposite jaw intermediate its length, and having a transverse bore formed through

said enlarged portion thereof, a block journaled in said transverse bore, said first 25 named jaw having a vertical bore intersecting said transverse bore, and the second jaw having a vertical bore substantially in alignment with the vertical bore of the first jaw, the vertical bore of the second jaw being intersected by a transverse opening in the second 30 jaw, an adjusting rod having the upper end portion thereof journaled in said vertical bore of the second jaw above the transverse opening in said second jaw and having 35 a screw portion extending loosely in said vertical bores of said jaws and in threaded engagement with a transverse bore in said block, and an operating wheel rigid with said adjusting rod and protruding from 40 said transverse opening in the second jaw, and an expansion spring disposed between said jaws rearwardly of the extremities of the furcations of the head portion of said body of the wrench.

GUY H. MILLER.
